ELECTRON DISCHARGE DEVICE

Percy L. Spencer, West Newton, Mass., assignor
to Raytheon Manufacturing Company, Newton,
Mass., a corporation of Delaware

Application March 21, 1945, Serial No. 583,922

9 Claims. (Cl. 250—27.5)

1

This invention relates to an electron discharge tube of the type adapted to generate ultra-high frequency oscillations and more particularly to one in which the frequency of one or more resonant circuits within the tube determines the frequency of the oscillations produced.

In such devices, it is desirable to be able to tune the tube so as to vary the frequency of the oscillations generated by the tube. It is also desirable that the tuning arrangement have substantially in inertia so that the frequency generated by the tube may be modulated at a very high rate. In this way the tube may be frequency-modulated in accordance with a desired signal variation.

One of the objects of this invention is to provide a novel and efficient means for varying the frequency oscillations generated by the tube.

Another object of this invention is to devise such a means which is substantially inertialess.

The foregoing and other objects of the invention will be best understood from the following description of exemplifications thereof, reference being had to the accompanying drawings wherein:

Fig. 1 is a transverse section through a magnetron constructed in accordance with my invention, said section being taken along line 1—1 of Fig. 2;

Fig. 2 is a transverse cross section taken along line 2—2 of Fig. 1;

Fig. 3 is a fragmentary view partly broken away of an alternative tuning arrangement embodying my invention; and

Fig. 4 is a transverse sectional view of a modified grid structure which may be utilized in my invention.

Referring to the drawings, there is shown a magnetron comprising a hollow cylindrical block 1, of conductive material such as copper, closed at its upper and lower ends by caps 2 and 3, likewise formed of conductive material. The hollow cylindrical block 1 has formed upon its interior surface a central annular projection 4 to which is soldered a plurality of suitably spaced radially disposed plates or arms 5. The arms 5, block 1, and end caps 2 and 3 constitute the anode structure. The interior ends of the arms 5 form anode faces for receiving electrons emitted from a cathode 6 centrally disposed within the anode structure.

The cathode 6 is preferably of the indirectly heated oxide-coated, thermionic, type provided with an outer electrically conducting sleeve 7 within which is contained a heater coil (not

2

shown), the end conductors 9 and 10 of which project from opposite ends of the cathode 6. One of the said conductors, the conductor 10 for example, may be connected to said outer conductive sleeve 7 whereas the other conductor 9 is insulated from said sleeve. Light conductive shields 11 and 12 are preferably mounted at the outer ends of the cathode sleeve 7 so as to prevent electron beams from being projected outwardly toward the end caps 2 and 3.

The cathode 6 is supported by a pair of lead-in conductors 13 and 14 connected respectively to the conductors 9 and 10. The lead-in conductors 13 and 14 are sealed through glass seals 15 and 16 mounted respectively in the outer ends of conducting pipes 17 and 18 which, in turn, are hermetically sealed through the wall of block 1.

When a tube as described above is placed between suitable magnetic poles 19 and 20, the cathode heater is energized, and a suitable voltage is impressed between the cathode and the anode structure, oscillations will be generated. Each pair of alternate anode arms 5 together with the portion of the block 1 therebetween constitute a cavity resonator. Each cavity resonator contains a certain amount of capacitance between the arms 5 and also a certain amount of inductance. This capacity and inductance primarily determine the resonant frequency of the cavity resonator and thus the frequency of the oscillations generated. These oscillations may be led out of said device by a coupling loop 21 extending into one of the cavity resonators. One end of the coupling loop is connected to the inner end of the conducting pipe 22 which is hermetically sealed through the wall of the block 1. The other end of said coupling loop is connected to a conductor 23 which extends through said pipe 22 and emerges through a glass seal 24 carried by the outer end of said pipe 22. The conductor 23 together with an external cylinder pipe (not shown) connected to the pipe 22 form a coaxial conductor transmission line through which the oscillations may be led to a suitable utilization device.

In order to reinforce the main frequency at which the device is intended to oscillate and to suppress spurious oscillations, each alternate anode arm 5 is connected at one end thereof by a conducting strap 25. By the term "strap" I intend to include an elongated conductor of any cross-sectional shape, here shown as rectangular. At the same end of the anode structure, the intervening alternate anode arms are connected by a similar strap 26. This insures that the volt-

ages at the alternate anode arms are maintained in phase with each other. In order to avoid spurious oscillations due to voltage differences arising because of the length of the anode arms along the axis of the tube, those anode arms which are interconnected by the strap 25 are similarly interconnected by a strap 27 at the lower ends of said arms, while those anode arms which are interconnected by the strap 26 are similarly interconnected by a strap 28. It will be noted that a capacity exists between the straps 25 and 26 and likewise between the straps 27 and 28. These capacities constitute a part of the capacity of each of the resonant cavities as described above.

Also sealed through the wall of the block 1 adjacent one end thereof is a conducting pipe 29 within which is mounted a central conductor 30 so as to form a concentric transmission line therewith. The inner end of the conductor 30 may be connected to a conductor 31 of reduced diameter which, in turn, is connected to one of the straps, for example, the strap 25. It will be noted that the strap 25 will have impressed thereon the voltage conditions at the end of one set of alternate anode arms. The pipe 29, on the other hand, will have impressed upon it the voltage conditions of the anode block 1 which will be substantially the voltage conditions existing at the back of each cavity resonator. In this way, the oscillating voltage which is generated by the tube will be impressed on the concentric transmission line 29-30. At the outer end of the conductor 30, there is mounted a hollow conducting sleeve 32 preferably of nickel. This sleeve is externally coated with thermionic emissive oxides 33 whereby the sleeve 32 is enabled to function as a thermionic cathode. Within the sleeve 32 is supported a heating filament 34, the outer ends 35 of which extend through a glass stem 36 sealed in the outer end of the pipe 29. Thus, when the conductors 35 are connected to a suitable source of energy such as a battery 37, the filament 34 raises the temperature of the sleeve 32 to a point at which the coating 33 emits electrons.

When oscillations are generated by the magnetron, the oscillatory voltage will be propagated through the concentric transmission line 29-30. When this voltage is of the proper phase to make the pipe 29 positive with respect to the conductor 30 at the sleeve 32 electrons will flow from the sleeve 32 through the intervening space to the pipe 29. This electronic flow will tend to cause this portion of the concentric transmission line to act as a low impedance termination and therefore the concentric transmission line 29-30 will act as a stub line terminated by a low impedance end.

In order to introduce tuning variations I surround the sleeve 32 with a grid 38. This grid preferably consists of a winding of fine wire supported on a conducting standard 39. The outer end of this standard is likewise sealed through the stem 36 so as to provide an external electrical connection to the grid. The grid 38 is of the so-called "variable mu" type. In Fig. 2 the grid 38 is shown as having a variable pitch winding, the pitch of the winding increasing as the distance from the block 1 increases. Thus as the grid 38 is made more negative with respect to the sleeve 32, electronic flow will first be cut off at the end closest to block 1. If the voltage of the grid becomes more negative, emission will

be cut off at successive points along the sleeve 32 further removed from the block 1.

Preferably, I make the distance "L" between the center of the emitting coating 33 and the point at which the conductor 31 is connected to the strap 25 substantially equal to λg which is the wave length in the transmission line of the average oscillations generated by the tube. I also prefer to make the length d of the coating 33 substantially equal to

$$\frac{\lambda g}{2}$$

A concentric transmission line terminated by 15 a low impedance end and having a length substantially equal to one wave length will reflect a relatively low resistive impedance into the cavity resonators of the magnetron. Thus, if the voltage on the grid 38 is set so that cut-off 20 of the electronic flow occurs at the center of the coating 33, the concentric transmission line 29-30 will appear substantially as such a resistive impedance. If however the voltage on the grid 38 is made less negative, cut-off will 25 occur closer to the block 1 and the effective length of the stub line will be shortened. This will produce the result that the stub line will reflect an inductive impedance into the cavity resonators of the magnetron. On the other hand, if 30 the voltage on the grid 38 is made more negative, cut-off will occur further away from the block 1 and the stub line will reflect a capacitative reactance into the cavity resonators. Thus merely by varying the potential on the grid 38, varying 35 amounts of either inductive or capacitative impedance may be reflected into the cavity resonators. This will change the natural frequency at which these cavity resonators tend to oscillate and thus the desired tuning of the magnetron 40 will occur.

Any desired arrangement for introducing the necessary voltage variations on the grid 38 may be utilized. This is shown diagrammatically in Fig. 2 as a battery 61 having a potentiometer 49 connected across it. The positive end of the battery is connected to the pipe 29 while an adjustable tap 41 is connected through a current-limiting resistance 62 to the grid standard 39. By adjusting the tap 41, the voltage on the grid 38 may be varied so as to produce tuning. Of course it is to be understood that the voltage variation on the grid may be produced by any desired means such as, for example, a signal variation of any desired frequency. For example, frequency stabilization may be secured by making the voltage variation on the grid 38 responsive to the deviations of the frequency of the oscillations generated by the magnetron from a desired frequency. The grid 38 may take any one of a variety of forms as long as it shifts the cut-off value along the grid in response to voltage variations therein. For example, an alternative form of grid is shown in Fig. 4. In this arrangement the grid turns are substantially uniform in pitch but gradually increase in diameter from one end to the other. Various other equivalent constructions whereby a grid having variable cut-off along its length may be devised.

Instead of utilizing a single thermionic cathode along which the electronic discharge cut-off may be varied, an alternative arrangement such as shown in Fig. 3 may be utilized. In this arrangement the same reference numerals are used where parts are identical with those shown in the embodiment of Figs. 1 and 2. In Fig. 3 a

first cathode sleeve 42 is mounted at the end of the central conductor 30, this sleeve being similar to sleeve 32 of Fig. 2 and being coated with a length of emissive oxide coating 43. The other end of the sleeve 42 has mounted thereon a hollow tubular section 44 of conducting material. Thus tubular section 44, in turn, carries a cathode sleeve 45. This sleeve 45 is similar to the sleeve 43 and similarly carries a short-coated section 46 of emissive oxides. The sleeves 42 and 45 may be heated by heating filaments 47 and 48, respectively, connected in series and mounted within said sleeves 42 and 45. The outer ends 49 and 50 of the heating filaments 47 and 48 are sealed through the stem 36. A substantially uniformly wound grid 51 surrounds the cathode sleeve 42 and a similar grid 52 surrounds the cathode 45. These grids are mounted respectively on grid standards 53 and 54 which are likewise sealed through the stem 36.

In this latter arrangement, if grid 51 is biased so as to permit electronic flow between the emitting section 43 and the pipe 29, the concentric line will be terminated substantially at the emitting section 43. If however, the grid 51 is biased to cut off the electronic flow and the grid 53 is biased so as to permit electronic flow from the emitting section 46, the concentric line will be terminated substantially at said emitting section 46. A variation in the length of the termination of such a stub line through substantially a quarter wave length will produce substantially a maximum of variation in the reactive impedance reflected by the stub line into the cavity resonators of the magnetron. Thus if the distance b between the emitting sections 43 and 46 is made substantially equal to a quarter wave length, substantially maximum tuning may be effected by shifting the emission from one cathode to the other. Instead of having an abrupt shift of the terminus of the concentric line from one cathode to the other, such transfer is preferably made gradually and in this way tuning may be accomplished over the entire range afforded by the two limits of the effective termination of the concentric line. This is illustrated diagrammatically in Fig. 3 by the provision of two batteries 63 and 64, respectively having their positive terminals connected together and having two resistances 55 and 56 connected respectively across batteries 63 and 64, respectively. An adjustable tap 57 on the resistance 55 is connected to the grid standard 53 while an adjustable tap 58 on the resistance 56 is connected to the grid standard 54. The two taps 57 and 58 may be moved simultaneously by a common actuating member 59. This arrangement provides a potentiometer in which one grid is made progressively more negative while the other grid is made progressively less negative. In the extreme position of actuation of member 59, one of the grids will permit a full conduction while the other grid will cut off conduction. The other limit of adjustment of the member 59 will reverse the conditions at the grids. Intermediate positions of adjustment will represent intermediate conditions of tuning. Here, likewise, it is to be understood that the variations in voltage on the grids 51 and 52 may be accomplished automatically in response to any desired variation.

Of course it is to be understood that this invention is not limited to the particular details as described above inasmuch as many equivalents will suggest themselves to those skilled in the art.

What is claimed is:

1. An electron-discharge device comprising a cavity resonator, means adjacent thereto for exciting said resonator to produce oscillations therein, a concentric transmission line coupled to said cavity resonator, said line comprising a hollow outer conductor enclosing a central conductor, an electron emissive section on said central conductor at a predetermined position removed from the point at which said line is coupled to said resonator and means adjacent said emissive section for cutting off the electron flow from said emissive section to said outer conductor at variable points along the length of said emissive section whereby the effective impedance of said line as reflected into said cavity resonator is varied.
2. An electron-discharge device comprising a cavity resonator, means adjacent thereto for exciting said resonator to produce oscillations therein, a concentric transmission line coupled to said cavity resonator, said line comprising a hollow outer conductor enclosing a central conductor, an electron emissive section on said central conductor at a predetermined position removed from the point at which said line is coupled to said resonator and a control electrode adjacent said emissive section.
3. An electron-discharge device comprising a cavity resonator, means adjacent thereto for exciting said resonator to produce oscillations therein, a concentric transmission line coupled to said cavity resonator, said line comprising a hollow outer conductor enclosing a central conductor, an electron emissive section of substantial length on said central conductor at a predetermined position removed from the point at which said line is coupled to said resonator and a control electrode adjacent said emissive section, said control electrode having a cut-off characteristic which varies from one end of said emissive section to the other end thereof, whereby the effective length of said emissive section capable of passing electrons to said outer conductor may be varied to vary the effective impedance of said line as reflected into said cavity resonator.
4. An electron-discharge device comprising a cavity resonator, means adjacent thereto for exciting said resonator to produce oscillations therein, a concentric transmission line coupled to said cavity resonator, said line comprising a hollow outer conductor enclosing a central conductor, an electron emissive section of substantial length on said central conductor at a predetermined position removed from the point at which said line is coupled to said resonator, the length of said emissive section being approximately a quarter of the wave length of the average oscillations generated in said cavity resonator and a control electrode adjacent said emissive section, said control electrode having a cut-off characteristic which varies from one end of said emissive section to the other end thereof, whereby the effective length of said emissive section capable of passing electrons to said outer conductor may be varied to vary the effective impedance of said line as reflected into said cavity resonator.
5. An electron-discharge device comprising a cavity resonator, means adjacent thereto for exciting said resonator to produce oscillations therein, a concentric transmission line coupled to said cavity resonator, said line comprising a hollow outer conductor enclosing a central conductor, a pair of electron emissive sections on said central conductor spaced from each other

and from the point at which said line is coupled to said cavity resonator and means adjacent said emissive sections for regulating the electron flow from each of said emissive sections to said outer conductor whereby the effective impedance of said line as reflected into said cavity resonator is varied.

6. An electron-discharge device comprising a cavity resonator, means adjacent thereto for exciting said resonator to produce oscillations therein, a concentric transmission line coupled to said cavity resonator, said line comprising a hollow outer conductor enclosing a central conductor, a pair of electron emissive sections on said central conductor spaced from each other and from the point at which said line is coupled to said cavity resonator and means adjacent said emissive sections for regulating the electron flow from each of said emissive sections to said outer conductor in opposite directions whereby the effective impedance of said line as reflected into said cavity resonator is varied.

7. An electron discharge device comprising a cavity resonator, means adjacent thereto for exciting said resonator to produce oscillations therein, a concentric transmission line coupled to said cavity resonator, said line comprising a hollow outer conductor enclosing a central conductor, a pair of electron emissive sections on said central conductor spaced from each other and from the point at which said line is coupled to said cavity resonator and a control electrode adjacent each of said emissive sections for regulating the electron flow from each of said emissive sections to said outer conductor whereby the effective impedance of said line as reflected into said cavity resonator is varied.

8. A magnetron comprising a hollow conducting member, a cathode centrally located therein, a plurality of spaced radial arms extending inwardly from said hollow member and terminating adjacent said cathode, alternate anode arms being connected together by a conducting strap adjacent one end of said arms, a concentric transmission line comprising a hollow outer conductor

enclosing a central conductor, said central conductor being connected to said strap, said outer conductor being connected to said hollow conducting member, an electron emissive section on said central conductor at a predetermined position removed from the point at which said central conductor is connected to said strap and means adjacent said emissive section for regulating the electron flow from said emissive section to said outer conductor.

9. A magnetron comprising a hollow conducting member, a cathode centrally located therein, a plurality of spaced radial anode arms extending inwardly from said hollow conducting member and terminating adjacent said cathode, alternate anode arms being connected together by a conducting strap adjacent one end of said arms, a concentric transmission line comprising a hollow outer conductor enclosing a central conductor, said central conductor being connected to said strap, said outer conductor being connected to said hollow conducting member, a pair of electron emissive sections on said central conductor spaced from each other and from the point at which said central conductor is coupled to said strap and means adjacent said emissive sections for regulating the electron flow from each of said emissive sections to said outer conductor.
